[57] CLAIM

The ornamental design for an extender handle for a
chain saw, as shown and described.

DESCRIPTION

FIG. 1 is a front top perspective view of an extender
handle for a chain saw, the broken line showing of the
saw is for illustrative purpose only and form no part of
the claimed design;

FIG. 2 is a top view, as related to the back, of the exten-
der handle of FIG. 1, the handle being 180 degrees from
the view of FIG. 1;

FIG. 3 is a left view, as related to the back, of the exten-
der handle of FIG. 1;

FIG. 4 is a back view of the extender handle of FIG. 1;
FIG. 5 is a right view, as related to the back, of the exten-
der handle of FIG. 1; and,

FIG. 6 is a bottom view of the extender handle of FIG.
1.
